(Cl. D9—2)

To all whom it may concern:

Be it known that we, Stephen A. Crosby and George C. Seeger, citizens of the United States, residing at Chicago, county of Cook, and State of Illinois, have invented a new, original, and ornamental Design for an Electric Portable Rubbing Machine or the like, of which the following is a specification, reference being had to the accompanying drawings, forming a part thereof, in which:

Figure 1 is a side elevational view of an electric portable rubbing machine, or the like, showing our new design; Fig. 2, a top plan view thereof; Fig. 3, a front elevational view; and Fig. 4, a rear elevational view of the same.

We claim:

The ornamental design for an electric portable rubbing machine, or the like, as shown,

STEPHEN A. CROSBY.
GEORGE C. SEEGER.
